UNITED STATES PATENT OFFICE.

THOMAS SLATTER, OF SAN FRANCISCO, CALIFORNIA.

FOLDING UMBRELLA.

1,280,568.

Specification of Letters Patent.

Patented Oct. 1, 1918.

Application filed July 26, 1916. Serial No. 111,394.

To all whom it may concern:

Be it known that I, THOMAS SLATTER, a citizen of the United States, residing at city and county of San Francisco and State of California, have invented new and useful Improvements in Folding Umbrellas, of which the following is a specification.

This invention relates to a folding umbrella and particularly to an improvement over my former patent entitled Folding umbrella, issued May 18, 1915, numbered 1,139,913.

The object of the present invention is to improve the structure shown in my former patent and particularly to provide a construction which will permit a more rigid connection between the umbrella rod and the foldable and detachable members.

Further objects will hereinafter appear.

20 The invention consists of the parts and the construction and combination of parts as hereinafter more fully described and claimed, having reference to the accompanying drawings in which:—

25 Figure 1 is the central vertical section showing the umbrella assembled.

Fig. 2 is a similar section showing the umbrella in the folded position.

30 Fig. 3 is a detailed exterior view looking at right angles to Fig. 1.

Fig. 4 is a detailed view showing the connection between the umbrella rod and the handle.

35 Referring to the drawings in detail it will be seen that the umbrella proper consists primarily of a handle section A, a tubular rod 2, and an extension tip 3.

The ribs connected with the stretchers of the umbrella are pivotally secured as at 4 40 within a bell shaped cap 5, which in turn is secured to the lower end of the tubular rod 2, and upper and lower latches 7 and 6 are provided to secure the ribs in the extended or folded position.

45 The tip extension is foldable with relation to the tubular rod and the umbrella handle is detachable to permit reduction of the structure as a whole in length for convenience of packing, carrying, etc. This is accomplished in the following manner:

50 Suitably secured to the handle A is a short rod extension 8 and pivotally mounted in a slot formed in said rod is a spring actuated latch member 9. The rod carrying the handle is inserted in the upper end of the tubu-

lar rod when the handle is applied, and a slot 10 is formed in the tubular rod 2 with which the latch engages to form a lock between the tubular rod and handle carrying rod. 60

For the purpose of reinforcing and strengthening the connection formed between the tubular rod and handle, and also for the purpose of providing means by which the tip 3 may be operated, a sleeve 65 member 11 has been provided. This sleeve is slidably mounted on the tubular rod, and the movement of same is limited in one direction by a pin 12 which passes through a pair of slots 13 formed in the tubular rod, 70 and in the opposite direction by the latch 9 and handle A. A flexible connection is formed between the pin 12, with connected sleeve 11, and the tip 3 by a wire rod 14, and a pair of links 15 and 16. By sliding the 75 sleeve to or away from the handle A, movement is transmitted through the rod 14 and links 15 and 16 either to eject the tip with relation to the lower end of the tubular rod so that it may be folded over as shown in 80 Fig. 2, or inserted as shown in Fig. 1. The latch 9 serves the function of a triple lock as it not only secures the umbrella handle against removal, but also the sleeve with connected rod 14 and tip 3. It will at the 85 same time reinforce the connection between the handle and tubular rod, thus producing a rigid connection at this point. For the

purpose of reducing any turning tendency of the handle with relation to the rod 2, a 90 pin 18 has been provided. This pin is secured in the rod extension 8 and projects sufficiently far beyond the face of the rod 8 to permit it to engage with slots 19 formed both in the tubular rod and the sleeve 11. A 95

similar connection is formed between the tip 3 and the bell shaped cap 5 by providing a groove or key-way 20, on the inner end of the tip which engages with a pin or lug projection 21 formed on the cap; turning movement of the tip with relation to the rod is in this manner prevented. The bell shaped cap 5 provided may be secured to the lower end of the tubular rod in any suitable manner, but preferably by the screw connection 100

105 shown. The upper end of the cap is sufficiently extended as at 22 to cover the pivotal connections 4 of the ribs, in this manner forming a protection for same and the covering which is attached thereto. Formed on 110

the tip 3 adjacent its inner end, is an annular collar 23 which is cone shaped to form a fit with a cone shaped projection 24 formed on the lower end of the cap 5. This structure 5 forms a joint which prevents admission of water or grit between the tip and rod, and at the same time forms rigid base for the tip which increases the stability of the structure as a whole.

10 In operation when it is desired to fold the umbrella, it is only necessary to depress the latch 9. The sleeve 11 is in this manner released and may then be pushed down on the tubular rod away from the handle. This 15 movement is transmitted through the rod 14 and links 15 and 16, to eject the umbrella tip which may then be folded over as shown in Fig. 2. The handle is next extracted by again depressing the latch 9 and the structure 20 as a whole may be placed in a covering and packed away in a comparatively small space, as the length of the structure is considerably reduced.

25 The improved features of the present invention is the provision of the bell shaped cap 5 which coöperates with the tip 3 to form a water tight joint at this point. It furthermore serves as a connection and a projecting member for the ribs and covering 30 and also reinforces and strengthens the structure as a whole at this point. The provision of the pin 18 is also an important feature as it coöperates with the tubular rod and sleeve 11 to positively prevent turning 35 movement of the handle with relation to the connected parts.

40 The materials and finish of the several parts of the structure may otherwise be such as the experience and judgment of the manufacturer may dictate.

45 I wish it understood that various changes in form, proportions, and minor details of construction may be resorted to within the scope of the appended claims, and that I do not wish to limit myself to the specific design or construction here shown.

Having thus described my invention, what I claim and desire to secure by Letters Patent is—

50 1. The combination with a tubular rod and a bell-shaped cap secured on the lower end of the rod having an annular shoulder formed thereon and a tapering extension, a rod tip adapted to be inserted in the lower 55 end of the tubular rod, and an annular tapering collar on the rod tip adapted to seat on the annular collar of the bell-shaped cap and inclose the tapering extension to

form a water-tight joint between the rod tip and the interior of the tubular rod. 60

2. In a folding umbrella, the combination with a tubular rod, of a bell-shaped cap secured on the lower end of the rod, a plurality of connected ribs and stretchers pivotally connected with the rod, the pivotal ends of the ribs being inclosed by the cap, a rod extension or tip adapted to be inserted in the lower end of the tubular rod, means for securing said tip against removal, an annular flange formed on the tip adapted 70 to coöperate with the bell-shaped cap to form a water-tight joint between the tip and the tubular rod, and means for locking the tip against turning movement, said means comprising a projection on the cap 75 adapted to enter a groove formed in the tip.

3. The combination with a tubular rod and a bell-shaped cap secured on the lower end of the rod having an annular shoulder formed thereon and a tapering extension, a rod tip adapted to be inserted in the lower end of the tubular rod, an annular tapering collar on the rod tip adapted to seat on the collar of the bell-shaped cap and inclose the 85 tapering extension to form a water-tight joint between the rod tip and the interior of the tubular rod, means for securing the rod tip against endwise removal, and means for securing said tip against turning with 90 relation to the tubular rod.

4. The combination with a tubular rod and a bell-shaped cap secured on the lower end of the rod having an annular shoulder formed thereon and a tapering extension, a 95 rod tip adapted to be inserted in the lower end of the tubular rod, a tapering collar formed on the rod tip adapted to seat on the annular collar of the bell-shaped cap and inclose the tapering extension to form a water-tight joint between the rod tip and the interior of the tubular rod, means for securing the rod tip against endwise removal, and means for securing said tip against turning with relation to the tubular 100 rod, said last-named means comprising a peg on the bell-shaped cap adapted to enter a groove formed in the rod tip.

105 In testimony whereof I have hereunto set my hand in the presence of two subscribing 110 witnesses.

THOMAS SLATTER.
